UNITED STATES PATENT OFFICE.

AUGUST WEBER, SR., OF SCHENECTADY, NEW YORK, ASSIGNOR TO WEBER ELECTRIC COMPANY, OF SCHENECTADY, NEW YORK, A CORPORATION OF NEW YORK.

PULL-SOCKET FOR INCANDESCENT ELECTRIC LAMPS.

984,053.

Specification of Letters Patent. Patented Feb. 14, 1911.

Application filed March 21, 1908. Serial No. 422,389.

To all whom it may concern:

Be it known that I, AUGUST WEBER, Sr., a citizen of the United States, residing at Schenectady, county of Schenectady, and State of New York, have invented certain new and useful Improvements in Pull-Sockets for Incandescent Electric Lamps, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view in side elevation of an incandescent electric lamp-socket provided with my improved pull-attachment. Fig. 2 is a similar view showing the attachment applied for use with the socket in inverted position from that shown in Fig. 1. Fig. 3 is a vertical cross-section 25 taken on the broken line 3-3 in Fig. 1, the outline of the socket case being indicated by dotted lines, showing in solid lines a broken-away portion of the shell containing the slot for the key-shaft. Fig. 4 is a similar view taken on the broken line 4-4 in Fig. 2. Fig. 5 is an end view of the socket with the attachment applied thereto in a position with the socket at right angles to that shown in Figs. 1 and 2. Fig. 6 is a view similar to Figs. 3 and 4 taken on the broken line 6-6 in Fig. 5. Fig. 7 is a central, vertical, longitudinal section of the socket and pull-attachment taken on the plane of the broken line 7-7 in Fig. 3, 40 showing the circuit open. Fig. 8 is a similar view with the parts in the positions occupied just as the circuit is closed. Fig. 9 is a vertical cross-section taken on the broken line 9-9 in Fig. 7; through the pull-attachment.

The principal object of my invention is to provide an attachment or operating means, located outside of the case of an incandescent electric lamp-socket, whereby an intermittent step-by-step rotative movement can be imparted to the key-shaft of said socket by successive pulls upon a cord or chain.

Other objects of the invention will appear in connection with the following description. 55

Referring to the drawings, wherein the invention is shown in its preferred form, 1, represents the shell and, 2, the cap of an incandescent electric lamp-socket of a well known type, forming the case within which is contained the screw-shell, 3, adapted to receive the base of an incandescent electric lamp, and the switch-mechanism comprising in part the switch-block, 4, adapted to make and break the electrical connection between the switch-plates, 5 and 6, said block being movable by means of the key-shaft, 7, from one to the other of the two positions shown in Figs. 7 and 8, the switch-block being shown in position to close the circuit in Fig. 8, and with the circuit open in Fig. 7. The several opening or closing movements of the switch-block are accomplished by a movement thereof of 90 degrees. The switch-mechanism and screw-shell, 3, are mounted upon an insulating base, 8, which may be of any known form. The shell is provided with an insulating lining 10.

The parts of the lamp-socket thus far described constitute no feature of the present 80 invention, and may be varied as desired, the present invention being applicable to any incandescent electric lamp key-socket, the key of which is adapted to be operated by successive partial rotative movements of the 85 key-shaft in the same direction. Rotative movements are imparted to the key-shaft, 7, through a ratchet, 12, fixed upon said shaft, the end of said shaft being widened at, 13, anchored in the insulating hub, 27, of said 90 ratchet. The ratchet, 12, has four teeth arranged 90 degrees apart adapted to be engaged by a pawl, 14, pivotally mounted at, 15, upon the disk-segment, 16; said pawl being adapted to be yieldingly held against the 95 ratchet by a spring 17. The disk-segment, 16, is connected with a pull-chain, 18, leading exteriorly of the case, 19, of the pull-attachment through an aperture, 20, formed therein. The disk-segment, 16, is rotatively 100 mounted upon the inner member of a double insulating sleeve, 21, which incloses the key-shaft, the exterior of the outer member of which sleeve is angular in cross-sectional form, and adapted to fit within the slot, 22, 105 in the shell of the case for the lamp-socket,

which is the usual slot found in the ordinary key-socket to receive the shank of the insulating handle on the key-shaft.

The disk-segment, 16, is adapted to be operated by the chain, 18, in opposition to the force of the spring, 23, which is coiled around the inner member of the insulating sleeve, 21, having one end connected with said sleeve, and the other end offset to occupy an aperture, 24, in the disk-segment. When a pull is exerted upon the chain, 18, a partial rotative movement will be imparted to the disk-segment, 16, which will be transmitted through the pawl, 14, and ratchet, 12, to the key-shaft to operate the same. When the pull upon the chain is relieved, the spring, 23, will restore the disk-segment, 16, and pawl, 14, to their original position, a return movement of the ratchet, 12, being prevented by the spring-dog, 25, mounted upon the insulating disk, 26. The disk, 26, is shown integral with both the inner and outer members of the sleeve, 21, the spring, 23, occupying an annular groove between said inner and outer sleeve-members.

The hub of the ratchet, 12, is formed of insulating material integral with a disk, 27, adapted to close the outer open end of the case, 19, of the pull-attachment. The case, 19, which may be of sheet-metal, the disk-segment, 16, and parts mounted thereon, and the chain, 18, are all insulated from the switch-mechanism of the socket.

To operate the switch-mechanism, it is necessary only to exert a pull upon the chain, 18, until the switch-block has been moved from the open to the closed position, or vice versa, as the case may be.

The attachment can be applied to the case of the lamp-socket so as to operate by means of a downward pull in any position in which the socket may be used, with its axis horizontal or vertical. The adjustment for this purpose is accomplished by removing the shell of the lamp-socket, thereby leaving the insulating sleeve, 21, free to be rotatively adjusted relatively to the stationary parts of the lamp-socket, so that the attachment can be caused to assume, when the lamp-socket case is again applied, any of the positions shown in the several figures of the drawings, in all of which the attachment is arranged for a downward pull.

While I have shown and described my invention as applied to an ordinary incandescent electric lamp-socket, for which it is particularly adapted, for certain purposes of the invention it may be applied to other forms of electric switch-mechanism in the use of which are met conditions similar to those met in the use of incandescent electric lamp-sockets, wherein it is desirable that the switch-mechanism with its insulating support and the means for operating the switch-mechanism should be together insertible

within, and together removable from, the inclosing case.

What I claim as new and desire to secure by Letters Patent is—

1. The combination with an inclosing case comprising a shell provided with an open slot and a cap for the slotted end of said shell; and an insulating support and switch-mechanism mounted thereupon together insertible within, and together removable from, said case, said switch-mechanism having an operating member projecting through said slot exteriorly of the case; of intermittently-operating pull-mechanism located outside of said case and operatively connected with said exteriorly-projecting member; said pull-mechanism having a member engageable with said case whereby rotation of said member is prevented.

2. The combination with an inclosing case comprising a shell provided with an open slot and a cap for the slotted end of said shell; and an insulating support and rotary electric switch-mechanism mounted thereupon together insertible within, and together removable from, said case, said switch-mechanism having a rotatory operating shaft projecting through said slot exteriorly of the case; of an intermittently-operating pull-attachment connected with the exteriorly-projecting portion of said shaft and having a member engageable with the case whereby rotation of said member is prevented.

3. The combination with an inclosing case comprising a shell provided with an open slot and a cap for the slotted end of said shell; an insulating support and rotary electric switch-mechanism mounted thereupon together insertible within, and together removable from, said case, said switch-mechanism having a rotatory operating shaft projecting through said slot exteriorly of the case; of a pull-attachment comprising a reciprocatory member located outside of said case movable automatically in one direction and responsive to a pull in the opposite direction, a pull connected with said oscillatory member, and mechanism mounted upon said shaft whereby said shaft is partly rotated by a pull-induced movement only of said oscillatory member, said pull-attachment being removable from said case in connection with said insulating-support and switch-mechanism.

4. The combination with an inclosing case comprising a shell provided with an open slot and a cap for the slotted end of said shell; an insulating support and rotary electric switch-mechanism mounted thereupon together insertible within, and together removable from, said case, said switch-mechanism having a rotatory operating shaft projecting through said slot exteriorly of the case; of a pull-attachment

comprising a ratchet fixed upon said shaft exteriorly of said case, a pawl engageable with said ratchet, a pawl-carrying oscillatory member responsive to a pull in one direction to cause the pawl to operatively engage said ratchet, means for automatically inducing a return-movement of said oscillatory member, and a pull connected with said oscillatory member, said pull-attachment being removable from said case in connection with said insulating-support and switch-mechanism.

5. The combination with an inclosing case comprising a shell provided with an open slot and a cap for the slotted end of said shell; an insulating support and rotary electric switch-mechanism mounted thereupon together insertible within, and together removable from, said case, said 15 switch-mechanism having a rotatory operating shaft projecting through said slot exteriorly of the case; of a ratchet fixed upon said shaft exteriorly of said case; a pawl engageable with said ratchet; a pawl-carrying oscillatory member responsive to a pull in one direction to cause the pawl to operatively engage said ratchet; a spring connecting said oscillatory member with a support held in fixed relation to said case by engagement therewith; and a pull connected with said oscillatory member.

6. The combination with the inclosing case provided with an open slot; the switch-mechanism and an insulating support therefor contained within said case, said switch-mechanism having an operating shaft extending through said slot exteriorly of the case; of a ratchet fixed upon said shaft ex- 35

teriorly of said case; a pawl engageable with said ratchet; a pawl-carrying oscillatory member responsive to a pull in one direction to cause the pawl to operatively engage said ratchet; a pull connected with said oscillatory member; a sleeve inclosing said shaft where the same passes through said slot, 40 said sleeve having a polygonal exterior adapted to fit within said slot in different positions of rotative adjustment of the sleeve; and a spring connecting said oscillatory member with said sleeve.

7. The combination with the inclosing case provided with an open slot; the switch-mechanism and an insulating support therefor contained within said case, said switch-mechanism having an operating shaft ex- 45 tending through said slot exteriorly of the case; of a ratchet insulated from and fixed upon said shaft exteriorly of said case; a pawl engageable with said ratchet; a pawl-carrying oscillatory member insulated from said shaft and responsive to a pull in one direction to cause the pawl to operatively engage said ratchet; a pull connected with said oscillatory member; an insulating sleeve 50 inclosing said shaft where the same passes through said slot, said sleeve having a polygonal exterior adapted to fit within said slot in different positions of rotative adjustment of the sleeve; and a spring connecting said oscillatory member with said sleeve.

In testimony whereof, I have hereunto set my hand this 29th day of February, 1908.

AUGUST WEBER, SR.
